UNITED STATES PATENT OFFICE.

ANDREW FLOHR, OF SACRAMENTO, CALIFORNIA.

STOVE-PIPE.

SPECIFICATION forming part of Letters Patent No. 251,857, dated January 3, 1882.

Application filed August 27, 1881. (No model.)

To all whom it may concern:

Be it known that I, ANDREW FLOHR, a citizen of the United States, resident of Sacramento, in the State of California, have invented a new and valuable Improvement in Stove-Pipes; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation, partly in section. Fig. 2 is a side view of the pipes, showing the slide and slot. Fig. 3 is a detail view.

This invention has relation to stove-pipes; and it consists in the novel construction and arrangement of parts hereinafter fully described, and particularly pointed out in the claim.

Referring by letter to the accompanying drawings, A designates a stove or furnace; B, the first vertical section of the pipe provided with a pivoted damper, C. The first section B of the pipe has an opening, E, the bottom of which is on a level with the pivoted damper C when the latter occupies a horizontal plane, and a slide, F, closes the opening E or discloses it when necessary.

30 A horizontal section, H, is connected with the vertical section B of the pipe, and has its ends provided with removable caps I I'. A cylindrical sliding damper, J, having an opening, K, and a draw-rod, L, extending through the center of the cap I', is provided with a handle or knob, M, and a slotted disk, O, a pin or stud, P, projecting through the slot Q from the cap I', to regulate the distance to which the sliding damper J may be turned to discharge its 40 contents or to close the damper when neces-

sary. In discharging the contents of the cylinder the latter is drawn by the knob and draw-rod from beneath the upper vertical portion, scraping in its passage the soot in the horizontal portion of the pipe in which it slides, 45 and when the lower vertical section of the pipe is reached the slide is turned until the opening J registers with the lower vertical section, at which time the soot will be dropped either into a similar lower slide or onto the pivoted 50 damper C in the first section of the pipe, where only one horizontal and two vertical sections are employed.

The caps at the ends of the horizontal flues may be also removed and the pipes thoroughly 55 cleaned, without disconnecting the joints of pipe or taking them from the stove or furnace.

In bar-rooms and saloons long sections of pipe are frequently required, but the same devices may be applied as above described where 60 it may be necessary to employ forty or fifty feet of pipe.

Having thus fully described my invention, what I claim as new, and desire to secure by Letters Patent, is—

65 In a stove-pipe, the combination, with an upper and lower vertical section of pipe, of a horizontal section provided with removable end caps and a cylindrical sliding damper having a discharge-opening, a draw-rod, and a 70 knob having a slotted disk engaging a pin in the removable cap, substantially as specified.

In testimony that I claim the above I have hereunto subscribed my name in the presence of two witnesses.

ANDREW FLOHR.
